(57) **CLAIM**

The ornamental Design for a receptacle connector, as shown and described.

DESCRIPTION

FIG. 1 is a perspective view of a receptacle connector showing our new design;

FIG. 2 is a top plan view thereof;

FIG. 3 is a bottom plan view thereof;

FIG. 4 is a side elevational view of the right side thereof;

FIG. 5 is a side elevational view of the right side thereof;

FIG. 6 is a front elevational view thereof;

FIG. 7 is a rear elevational view thereof;

FIG. 8 is a perspective view of an alternate embodiment of our new connector design, with all other aspects of the connector being the same as for the first embodiment, except for the front elevational view; and,

FIG. 9 is a front elevational view of the connector of FIG. 8.
